DESIGN FOR A STOCKING

Joset Walker, New York, N. Y.

Application August 30, 1943, Serial No. 111,024

Term of patent 3½ years

To all whom it may concern:

Be it known, that I, Joset Walker, a citizen of the United States, residing in New York city, in the county of New York and State of New York, have invented a new, original, and ornamental Design for a Stocking, of which the following is a specification, reference being had to the accompanying drawing, forming part thereof.

Fig. 1 is a side view of a stocking showing my design, and

Fig. 2 is a fragmentary rear elevational view of the stocking shown in Fig. 1 as it appears when worn, illustrating the heel portion in detail.

The opposite side of the stocking is the same as the side shown on the drawing.

I claim:

The ornamental design for a stocking, substantially as shown and described.

JOSET WALKER.
